UNITED STATES PATENT OFFICE.

ARTHUR J. BRADLEY, OF SAN FRANCISCO, CALIFORNIA.

TORPEDO-NET.

1,301,641.

Specification of Letters Patent. Patented Apr. 22, 1919.

Application filed February 16, 1918. Serial No. 217,987.

To all whom it may concern:

Be it known that I, ARTHUR J. BRADLEY, a citizen of the United States, residing in the city and county of San Francisco and State of California, have invented a new and useful Improvement in Torpedo-Nets, of which the following is a specification.

My invention relates to torpedo nets for trans-oceanic vessels wherein an endless net 10 operates in conjunction with dispensing and receiving means to constantly retain a portion of the net stationary within the water and a distance from the side of the vessel.

The primary object of my invention is 15 to produce a submerged torpedo net for trans-oceanic vessels that will protect the vessel from broad-side torpedoes and at the same time reduce the towing resistance to a minimum.

20 A further object of the invention is to provide an invisible or submerged torpedo net of the character described that may be used during a trans-oceanic voyage without diminishing the speed of the vessel.

25 Another object of the invention is to provide a torpedo net of the character described that may be easily and readily moved inwardly toward the side of the ship to facilitate docking or boarding.

30 I accomplish these several objects by means of the device disclosed in the drawings forming a part of the present specification wherein like characters of reference are used to designate similar parts throughout 35 the said specification and drawings, and in which—

Figure 1 is a broken plan view of a vessel disclosing my improved net applied thereto;

Fig. 2 is a broken side elevation of Fig. 1;

40 Fig. 3 is a side elevation of one of the retaining blocks;

Fig. 4 is a top elevation thereof;

Fig. 5 is a front elevation on an enlarged scale of the left hand side of Fig. 3;

45 Fig. 6 is a broken sectional view taken on line 6—6 of Fig. 2 in the direction indicated.

Referring to the drawings the numeral 1 is used to designate an endless torpedo net 50 mounted to move, in a horizontal position, aboard a vessel 5 and from stern to bow. In its progress toward the bow the net 1 moves over rollers 2 supported by a suitable super-structure 3 and also over what is commonly known as a tension carriage 4 having rollers 7 and 8 thereon. The roller 8

has its bearings mounted upon a screw threaded shaft 9 whereby said roller 8 may be moved longitudinally to increase or decrease the tension of the endless net 1. 60

After passing over the tension carriage 4 the net 1 passes over horizontally disposed rollers 11 and 12 and from the said roller 12 passes downward through a forward well 14 to a roller 16 which is inclined downwardly 65 and outwardly at an angle of approximately forty-five degrees to change the direction of the net 1 at right angles to itself and in the same plane as the said net 1.

This device changes the position of the 70 net 1 so that it may be passed in a vertical position and laterally from the side of the vessel 1 to a series of retaining blocks or pulleys 17, after passing over a vertically disposed roller 18 at the lower opening of 75 the well 14, said blocks or pulleys 18 being arranged to engage the larger rope or thickened edges of the net 1.

The blocks or pulleys 18 are provided with rollers 21 grooved to engage and retain 80 the edges of the net 1 and at the same time permit the passage of the thinner web of said net between the peripheries or flanges of said rollers 21 adjacent the grooves therein. 85

The blocks or pulleys 17 are suspended at a distance from the sides of the vessel 5 by means of collapsible braces 22 terminating in internally threaded sleeves 23 which are screwed upon oppositely threaded portions 90 of longitudinal rods or shafts 24 rotatably mounted upon the sides of the vessel 5 and below the normal water line.

After passing through as many blocks or pulleys 17 as may be necessary to suspend 95 the net 1 in a vertical position at a distance from the sides of the ship the said net 1 is passed into a rear well 27 provided at the bottom thereof with an inclined roller similar to the roller 16 in the forward well 14 100 whereby the direction of the net 1 is changed to carry said net to the upper deck of the vessel 5 and onto the rollers 2 of the super-structure 3 hereinbefore described.

The rods or shafts 24 are provided with 105 worm gears 29 which are in engaging relation with worms 31 arranged upon a vertically disposed shaft 32 rotatably mounted upon each side of the vessel 5 and provided with a bevel gear 33 which meshes with a 110 similar bevel gear 34 upon a horizontally disposed counter shaft 37 provided with a

second bevel gear 38 meshing, in turn, with a bevel gear 39 upon the threaded shaft 9 of the tension carriage 4 hereinbefore described.

5 As the shafts 9 are rotated, by any suitable means, not shown, the horizontal shafts 24 on the sides of the vessel 5 are also rotated to spread the sleeves 23 and the inner ends of the braces 22 to move the blocks 17

10 inwardly toward the sides of the vessel 5 for boarding or docking purposes. The rotation of the shaft 9 simultaneously moves the rollers 8 to take up the slack occasioned by the inward movement of the net 1.

15 I have provided a rope or cable loop or connection 41 which extends between each pair of upper and lower blocks 17 so that any obstruction engaging the net 1 as it moves toward the rear of the vessel 5 will be removed from said net 1 by said loops 41.

20 A suitable motive power may be applied to the roller 7 to feed the net 1 from the stern toward the bow of the vessel 5 at the same rate of speed as that with which 25 said vessel 5 moves forward.

25 It will be observed that the net 1 will then pass from the forward end of the vessel 5 at the same rate of speed as the speed of said vessel 5, the net by this arrangement 30 appearing as if it were suspended stationary within the water.

35 Therefore, as the movement of the net 1 is such that the net appears to be stationary relatively to the water, it is evident that there will be substantially no towing resistance on the part of the net 1. It is also evident that the said net 1 will be received by the aft or rear well at the same rate of speed with which the said net has previously 40 passed from the forward well 14, or from the bow of the boat.

45 As the net travels so fast in the opposite direction of the vessel as to be, in appearance, stationary within the water it is evident that there will be substantially no friction between the water and net and consequently a resistance otherwise due to towing will be eliminated.

50 It is also obvious that as the net is submerged it will be substantially invisible.

It is also evident that the net may be easily and quickly moved inwardly toward the vessel 5 when said vessel is to be docked or boarded.

Having thus described my invention what 55 I claim as new and desire to secure by Letters Patent is—

1. A torpedo net for vessels comprising an endless net mounted to move on board in a horizontal position from the stern to bow, 60 and in a vertical position in the water from bow to stern; means for passing the net from the bow of the vessel and for turning said net from a horizontal to a vertical position; means for receiving the net at the 65 stern of the vessel and for turning said net from a vertical to a horizontal position; submerged collapsible means for slidably engaging the top and bottom edges of the net portion in the water to retain said portion at a distance from the side of the vessel; means for collapsing said submerged collapsible retaining means to move the net inwardly toward the side of the vessel to facilitate docking or boarding; and means 70 for simultaneously taking up the slack in the horizontal portion of the net on board occasioned by said inward movement of the vertically positioned portion of the net. 75

2. A torpedo net for vessels comprising 80 an endless net mounted to move on board in a horizontal position from stern to bow, and in a vertical position in the water from bow to stern; means for passing the net from the bow of the vessel and for turning 85 said net from a horizontal to a vertical position; means for receiving the net at the stern of the vessel and for turning said net from a vertical to a horizontal position; submerged collapsible means for slidably engaging the top and bottom edges of the net portion in the water to retain said portion at a distance from the side of the vessel; means for collapsing said submerged 90 collapsible retaining means to move the net inwardly toward the side of the vessel to facilitate docking or boarding; means for simultaneously taking up the slack in the horizontal portion of the net on board occasioned by said inward movement of the 95 vertically positioned portion of the net; and means for stripping objects from the net during its movement toward the stern of the vessel. 100

In witness whereof I hereunto set my signature. 105

ARTHUR J. BRADLEY.
